PORTABLE ELECTRIC CHARCOAL BROILER

Samuel M. Bernstein, Winnetka, Ill.

Application August 28, 1958, Serial No. 52,427

Term of patent 14 years

(Cl. D81—10)

Fig. 1 is a perspective view of a portable electric charcoal broiler showing my new design;

Fig. 2 is a front elevational view of the same;

Fig. 3 is an end view elevation of the same;

Fig. 4 is a top plan view of the same;

Fig. 5 is a rear elevational view of the same;

Fig. 6 is a view in elevation of the other end of the broiler; and

Fig. 7 is a bottom plan view of the same.

I claim:

The ornamental design for a portable electric charcoal broiler, substantially as shown.
